COUPLER

Edmund P. Kinne, Alliance, Ohio, assignor to
American Steel Foundries, Chicago, Ill., a cor-
poration of New Jersey

Application June 9, 1930, Serial No. 459,871

11 Claims. (Cl. 213—50)

This invention pertains to draft rigging for railway rolling stock, and more particularly to that class of draft rigging especially designed for application to the underframes of railway cars, and includes, in combination with car sills, means for connecting a coupler to the draft mechanism and for connecting the draft mechanism to the car underframe.

It is an object of this invention to provide, in combination, a vertical key connection adapted to permit relative movement between the yoke and the coupler, means for supporting and guiding at least one of the followers, and means for limiting the forward movement of one of said followers.

Another object is to provide a draft rigging so constructed and arranged as to transmit excessive loads to the car underframe without detriment to the latter, said draft rigging including a vertical key connection between the coupler and the yoke, a horizontal key connection between the follower and draft sills, and means for transmitting stresses to the draft sills.

Still another object is to obtain a strong and serviceable radial shank connection in the simplest possible manner; one which will have the least possible surfaces subject to wear which result in slack in the connection; one in which radial (or angling) action of the coupler shank is provided for while maintaining equalized pull on the yoke jaws in tension, and full butt end contact area and equalized pressure on draft gear or follower under buffing stresses.

Yet another object is to provide a construction wherein the pivotal action between the coupler and yoke is provided for by the same piece which connects them for pulling action; that is, the vertical key, wherein there are no superfluous connections with keys or small bearing pieces and wherein the vertical key is of ideal design to provide large bearing surface, free pivotal action and large area to resist shearing.

A further object is to provide a construction wherein generous bearing area is provided at key bearings and butt bearings insuring minimum wear, and wherein large sectional areas in tension, compression and shear are also provided.

A still further object of the invention is to provide a construction in which the coupler angles freely regardless of the compression in the draft gear to thereby permit coupling on curves without delay or effort, and to thereby eliminate transmission of the side movement to the coupler key to avoid wear of the key and keyways and

to prevent any blows on the cotter or other key fasteners.

A yet further object is to provide a coupler retaining the advantages of the standard A. R. A. coupler; one which includes an efficient guide to maintain the coupler shank in proper position, adequate provision for vertical angular movement without pinching the key in either the coupler or yoke, positive emergency connection in the event of yoke or draft gear breakage, removal and replacement of coupler and draft gear without taking down the entire draft attachments, and also to provide an arrangement which includes all of the advantages claimed for the so-called "swivel butt" arrangement, and includes additional advantages such as greater simplicity, increased strength, and increased bearing surfaces.

Another further object is to provide a construction which is inexpensive to make and maintain, one which fulfills all requirements of manufacture and service, and also is readily replaceable by parts of standard construction without material changes in the car or draft appliance.

A further additional object is to provide a coupler construction having the advantage of the radial coupler connection, though the construction may be applied to cars built for the Farlow attachments, whether a horizontal or vertical plane yoke be used.

With these and various other objects in view, the invention may consist of certain novel features of construction and operation, as will be more fully described and particularly pointed out in the specification, drawings and claims appended hereto.

In the drawings, which illustrate an embodiment of the device and wherein like reference characters are used to designate like parts—

Figure 1 is a longitudinal sectional top plan view of one application of the draft appliance in operative position with respect to the draft sills;

Figure 2 is a longitudinal sectional elevation of the draft appliance shown in Figure 1;

Figure 3 is a transverse sectional elevation taken substantially in the plane as indicated by the line 3—3 of Figure 1;

Figure 4 is a transverse sectional elevation, 105 with certain parts omitted, taken substantially in the plane as indicated by the line 4—4 of Figure 1;

Figure 5 is a fragmentary longitudinal sec- 110 tional top plan view of a modified form of draft

appliance showing the same in operative position with respect to draft sills;

Figure 6 is a longitudinal side elevation of the follower shown in Figure 5; and

5 Figure 7 is a fragmentary sectional top plan view showing a modified form of back stop casting associated with the draft sills and yoke rear end.

Referring first of all more particularly to the 10 form of draft appliance shown in Figures 1 to 4, inclusive, the draft sills 10 are connected to the back stop casting 12 by fastening means such as rivets 14, and to the transoms 16 as by means of the rivets 18, the ends of said sills being connected by the striking casting 20 provided with a lower substantially H-shaped portion 22 forming a support for the carry iron 24, the striking casting defining an opening 26 through which the coupler butt 28 extends. The striking casting is 15 provided with an inwardly extending flange 27 to which the floor 30 and the end sill 32 are secured as by means of rivets 34. The striking casting is also provided with an inwardly extending cheek plate portion 36 defining one end 20 of the keyways 38, the opposite end of the keyways 38 being defined by cheek plates 40 secured to the sills and defining aligned keyways 42. The plates 40 have widened portions 44 adjacent the end of the keyways 38 and the outer end of the 25 keyways 42 which extend inwardly of the sills 10 and provide an increased bearing surface for the transverse key 46 extending through the keyways 42 and the follower 48.

A vertical plane yoke 50 is disposed between 30 the sills having the end portion 52 connecting the upper and lower arms 54 and normally abutting the back stop casting 12. The yoke is of the hooded type having the upper and lower portions 56 connected by the vertical straps 58, 35 said straps being provided with aligned keyways 60 adapted to be disposed in way of the horizontal keyways 38 for the reception of a horizontal key in the event of an emergency where a horizontal key coupler may replace the coupler 40 28. The upper and lower portions 56 of the yoke are provided with vertically extending faces 62 which are disposed to contact the vertical faces 64 of the striking casting in case there is a failure of the draft gear. The upper and lower 45 portions of the yoke are provided with aligned keyways 66 which are parallel sided and are adapted to receive the elongated vertically disposed key 68, said key extending through elongated keyways provided in the coupler butt 28 which are substantially the same width in a 50 longitudinal direction as the key, said keyways in the coupler butt being preferably widened laterally at their outboard end (toward the left as viewed in Figure 1) for permitting angling 55 of the coupler. The lower portion of the key is provided with spaced rounded arms 70 adapted to straddle and have sliding engagement with the substantially round retainer 72 disposed in the depending members 74 and 76 forming the 60 cage, said members being integral with the yoke. 65

The rear of the coupler butt is rounded as at 70 78 to provide an arcuate surface cooperating with a complementary arcuate surface formed on the buffing piece or bearing block 80, said block being secured to the coupler butt by means of a tongue 75 67 embracing the key 68 and extending into a slot in the coupler butt, all as described in application Serial No. 318,350, filed November 10, 1928. The buffing piece has a flat rear surface 82 having bearing engagement with a corre-

sponding flat surface on the outboard end of the follower 48. The follower, as shown, is provided with marginal upstanding ribs 84 connected by longitudinal upwardly extending ribs 86, and said follower is provided with a keyway 88 for the reception of the horizontal key 46.

The follower is provided with outwardly extending arms 90 adapted to have cooperative relation with the sills or cheek plates whereby the follower is guided in longitudinal movement so that it will not angle with respect to the sills, and, as the members 90 embrace the key 46, an increased bearing area is provided to prevent bending of the key by materially reducing the bending moment on the key. The forward end 90 of the yoke is widened as at 92 to prevent angling of the yoke to follow the coupler, and the rear end of the yoke is guided by means of the blocks 94 secured to the carry iron 96 by means 95 of the rivets 98.

In buff, the stress is transmitted from the coupler butt to the buffing piece, and from the buffing piece to the follower, and from the follower through the draft gear (indicated by the dot and dash lines), and the stress is then transmitted 100 through the vertical strap 52 to the back stop casting 12 and thence to the sills.

In draft, of course, the stress is transmitted through the vertical key 68 to the yoke, the yoke transmitting the stress through the rear strap 105 52 and through the draft gear to the follower 48, from the follower 48 to the horizontal key 46, and to the sills through the widened stops 100 defining the outboard end of the keyway 42, it being seen that the stress thus transmitted will be transmitted over the widened rear edge 102 of the follower 48, the extensions in this edge being formed by means of the members 90.

In the construction shown in Figures 5 and 6, the yoke, which is substantially of the same construction as has already been described, is, however, of lesser width adjacent the hood. That is, the members 104 corresponding to the members 92 are not so close to the sills, and, in order to provide a guide for the forward end of the yoke or the hooded end of the yoke, the follower 106 is provided with forwardly extending prongs 108 which cooperate with the inside faces of the cheek plates and with the hooded end of the yoke to maintain the yoke in central position. As before, this follower is provided with a rear edge 110 corresponding to the extended rear edge formed by the members 90 and the same extends substantially the entire distance between the sills so that the bending moment on the key is reduced.

In the construction shown in Figure 7, the backstop casting 112 is secured to the sills 10 by means of the rivets 14, as before, said backstop casting being a combination backstop and center bolster 135 filler, and being arranged with a center slot 114 to receive and guide the rear end of the yoke 50. In this arrangement portions 116 of the backstop casting are extended on either side of the yoke end, and the surfaces 118 formed thereon 140 are in alignment and form a substantially continuous rear bearing surface with the draft gear engaging surface 120 of the yoke. This arrangement has the feature of providing increased bearing area for the draft gear and also providing a 145 strong stop at the center of the draft gear which is of great value in connection with gears having control plungers or the like, and it will be seen that this construction forms a strong stop at the outer edges of the draft gear near the sill, which 150

is of great value with the use of gears of maximum strength at this location.

It is to be understood that I do not wish to be limited by the exact embodiments of the device shown, which are merely by way of illustration and not limitation, as various and other forms of the device will of course be apparent to those skilled in the art without departing from the spirit of the invention or the scope of the claims.

10. I cla'm:

1. In a draft mechanism, the combination of a yoke adapted to carry a draft gear, and a front follower member for said gear, said member having guide arms exteriorly of the yoke and engageable therewith to prevent relative lateral movement between said yoke and follower.

2. In a draft mechanism, the combination of a yoke adapted to carry a draft gear, and a front follower member for said gear, said member having arm members exteriorly of said yoke and engageable with the same to prevent relative lateral movement between said yoke and follower.

3. In a draft mechanism, the combination of a yoke adapted to carry a draft gear and provided with a hooded head portion, and a front follower member for said gear, said member being provided with guide arms exteriorly of said yoke and engageable with said head portion to prevent relative lateral movement between said yoke and follower.

30. 4. In a draft mechanism, the combination of a yoke adapted to carry a draft gear and provided with a hooded head portion, said portion having side enclosure walls, and a front follower member for said gear, said member being provided with forwardly extending portions exteriorly of said side walls and engageable therewith to prevent relative lateral movement between said yoke and follower.

40. 5. In a draft mechanism, the combination of draft sills, a vertical yoke supported by said sills and provided with a hooded head portion, a coupler movably connected to said yoke and embraced by said hooded head portion, a draft gear carried by said yoke, and a front follower member for said gear abutting said coupler and movable therewith in buff, said member being disposed between said sills and held against lateral movement thereby, said member having guide portions interposed between said sills and hooded head and engageable with the latter to prevent lateral movement of said yoke relative to said follower.

45. 6. In a draft mechanism, the combination of draft sills, a vertical yoke supported by said sills and provided with a hooded head portion having side enclosure walls, a coupler movably connected to said yoke and embraced by said hooded head portion, a draft gear carried by said yoke, and a front follower member for said gear abutting said coupler and movable therewith in buff, said member being disposed between said sills and held against lateral movement thereby, said member being keyed to said sills, said member having

guide portions interposed between said sills and enclosure walls and engageable with the latter to prevent lateral movement of said yoke relative to said follower.

7. In a draft mechanism, the combination of draft sills, a vertical yoke supported by said sills and provided with a hooded head portion having side enclosure walls, a coupler movably connected to said yoke and embraced by said hooded head portion, a draft gear carried by said yoke, a front follower member for said gear abutting said coupler and movable therewith in buff, said member being disposed between said sills and held against lateral movement thereby, a key member movably mounted in said sills for supporting said follower member, said key member extending through said follower member rearwardly of the coupler abutting surface thereof, said follower member having guide portions interposed between said sills and enclosure walls and engageable with the latter to prevent lateral movement of said yoke relative to said follower.

8. In a draft mechanism, the combination of draft sills, a yoke disposed between said sills, a draft gear embraced by said yoke, and a front follower member for said draft gear disposed between said sills and held against lateral movement thereby, said follower having portions disposed between said sills and yoke and engaging the latter to prevent lateral movement thereof relative to said follower.

9. In a draft mechanism, the combination of draft sills, a yoke disposed between said sills and provided with a hooded head, a draft gear embraced by said yoke, and a front follower member for said draft gear disposed between said sills and held against lateral movement thereby, said follower having portions disposed between said sills and hooded head portion and engaging the latter to prevent lateral movement thereof relative to said follower.

10. In a draft mechanism, the combination of draft sills, cheek plates connected thereto, a yoke disposed between said sills, a draft gear embraced by said yoke, and a front follower member for said draft gear disposed between said sills and held against lateral movement thereby, said follower having portions interposed between said cheek plates and yoke and engaging the same to prevent lateral movement of said yoke relative to said follower.

11. In a draft mechanism, the combination of draft sills, cheek plates connected thereto, a yoke embraced by said sills and having a hooded head portion, a draft gear embraced by said yoke, and a front follower member for said draft gear disposed between said sills and held against lateral movement thereby, said follower having portions interposed between said cheek plates and said head portion and engageable therewith to prevent lateral movement of said yoke relative to said follower.
